3 Claims

ABSTRACT OF THE DISCLOSURE

To protect the plastic body of a water faucet which is susceptible to erosion by the chemicals in water, a sleeve is provided to separate the water from the plastic body of the faucet, thus materially reducing the erosive effect of the chemicals in water, such as chlorine. The metal insert which forms the water conduit is so constructed that it will not fill with the plastic of which the body is formed while that body is being cast.

An object of my invention is to provide a novel metal thimble or sleeve which is closed at both ends, so as to protect the inner hollow portion of the sleeve and prevent it from filling or partly filling with the plastic of which the body is formed.

Another object of my invention is to provide a novel sleeve forming the water conduit in a water faucet, this sleeve being constructed so that it can be readily drilled at both ends after the faucet body is cast, thus providing an open conduit from the water intake to the water outlet of the faucet.

Still another object is to provide a novel integrally cast sleeve or conduit which is simple in construction, inexpensive to manufacture, and which can be readily placed in the mold prior to the casting of the faucet body.

Other objects, advantages and features of invention may appear from the accompanying drawing, the subjoined detailed description and the appended claims.

In the drawing:

FIG. 1 is a perspective view of a water faucet in which the water conduit is integrally cast.

FIG. 2 is an open view of the body portion of the water faucet.

FIG. 3 is a sectional view taken on line 3—3 of FIG. 2 showing the sleeve or conduit before it is drilled.

FIG. 4 is a view similar to FIG. 3 but showing the water conduit or sleeve after it is drilled.

FIG. 5 is a perspective view of the sleeve or conduit.

Referring more particularly to the drawing, the numeral 1 indicates a valve body which is formed of a plastic, of the type which will permit chrome plating or the like. This type of plastic is quite susceptible to certain chemicals in the normal city water supply and, consequently, the body must be separated or protected

2

from the water which flows through that body. The body 1 includes a vertical bore 2 which receives the usual and well known faucet valve 3. An outlet port 4 is provided in the body 1 and is spaced from the intake port 2. A swing outlet pipe 5 is fitted in the outlet conduit 4 and is mounted and constructed in the usual and well known manner.

Since the water must flow from the intake 2 to the outlet 4, it is necessary to protect the plastic body 1, and this is accomplished as follows: A tubular metal sleeve 6 is embedded in the plastic body 1 at the time that body is cast and is, therefore, integral with that body. At the time the casting or molding operation occurs the sleeve 6 is closed at both ends, as shown at 7 and 8. This prevents any of the plastic material from entering the sleeve during the casting or molding operation. After the body 1 has cooled and set the sleeve 6 is drilled vertically, as shown at 9, thus opening the sleeve 6 at one end. At the other end a drill 10 is made, which opens the intake end of the sleeve 6 and thus permits water to flow horizontally through the sleeve from one end to the other. The plastic material of the body 1 is thus substantially protected against contact with the tap water and the body will thus not be eroded as quickly as if the body were not protected. Since the sleeve 6 is rigidly fixed in position, it is relatively simple to form the hole 9 by straight drill and to cut the hole 10 with an off-set or angle drill.

What is claimed is:

30. 1. An integrally cast conduit for a valve including a molded plastic body having spaced intake and outlet ports therein, a sleeve embedded in said body and extending between said intake and outlet ports.

35. 2. An integrally cast conduit for a valve as recited in claim 1, said sleeve being closed at both ends when molded in the body, and drillable at both closed ends to allow a passage therethrough, and communicating with the ports.

40. 3. An integrally cast conduit for a valve as recited in claim 1, said sleeve being tubular and extending horizontally between said intake and outlet ports.
